(57) **CLAIM**

The ornamental design for an office furniture, as shown and described.

DESCRIPTION

FIG. 1 is a front perspective view of an office furniture showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of detail 9 in FIG. 2.

The dash-dash broken lines shown in the drawings depict portions of the office furniture that form no part of the claimed design. The dot-dash broken lines in FIGS. 2 and 9 annotate the enlarged detail views of the office furniture and form no part of the claimed design.
